(57) **CLAIM**

The ornamental design for a dog muzzle, as shown and described.

DESCRIPTION

FIG. 1 is a front, right and top perspective view of a dog muzzle showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of the dog muzzle of FIG. 1, shown in condition of use.

FIG. 10 is an enlarged view of area 10 in FIG. 1;

FIG. 11 is an enlarged view of area 11 in FIG. 3; and,

FIG. 12 is an enlarged view of area 12 in FIG. 4.

The broken line showing of a dog in FIG. 9 is for the purpose of illustrating environmental scenario and forms no part of the claimed design. The dot-dash broken lines represent boundaries of the enlarged portions and form no part of the claimed design.

1 Claim, 12 Drawing Sheets
